UNITED STATES PATENT OFFICE.

CHARLES ROWLAND, OF QUINCY, ILLINOIS.

DESIGN FOR A DRAWER-PULL.

SPECIFICATION forming part of Design No. 15,698, dated January 6, 1885.

Application filed September 19, 1884. Term of patent 7 years.

To all whom it may concern:

Be it known that I, CHARLES ROWLAND, a citizen of the United States, residing at Quincy, in the county of Adams and State of Illinois, 5 have invented and produced a new and original Design for Drawer-Pulls, of which the following is a specification, reference being had to the accompanying drawings, forming part thereof.

10 The drawer-pull according to my design represents the form of a tortoise or tortoise-shell. The pedal extremities may represent securing means.

15 The design is illustrated in the accompanying drawings, in which Figure 1 is a perspective view of my design as applied to the front part of a drawer; Fig. 2, a section on the line α α of Fig. 3, and Fig. 3 a plan view of the design.

20 These views are necessary to fully illustrate my design.

Referring to the drawings, A designates the body of the drawer-pull, having the design of

a tortoise or tortoise-shell, and having a recess, a, upon the under lower portion. B designates the legs or feet of the tortoise, and C the head of the same.

The essential feature of the design is the representation of a tortoise-shell, and clips, as seen in Fig. 3, may be substituted instead of the lugs B.

The head C may be omitted without departing from the principle of my design.

The design presents a very pleasing and appropriate form for drawer-pulls or handles 35 for movable parts of furniture.

What I claim is—

The design for a drawer-pull herein described and shown, consisting of the representation of a tortoise having a recess, as a. 40

This specification signed and witnessed this 17th day of September, 1884.

CHARLES ROWLAND.
